UNITED STATES PATENT OFFICE.

CHARLES ALGERNON PARSONS AND HORACE LEONARD SHORT, OF NEWCASTLE-UPON-TYNE, ENGLAND; SAID SHORT ASSIGNOR TO SAID PARSONS.

MACHINE FOR SHAPING TURBINE-BLADES.

1,031,463.

Specification of Letters Patent.

Patented July 2, 1912.

Application filed March 18, 1907. Serial No. 363,160.

To all whom it may concern:

Be it known that we, CHARLES ALGERNON PARSONS and HORACE LEONARD SHORT, subjects of the King of Great Britain and Ireland, and residing at Heaton Works, Newcastle-upon-Tyne, in the county of Northumberland, England, have invented a certain new and useful Machine for Shaping Turbine-Blades, of which the following is 10 a specification.

This invention relates to means for shaping turbine blades and especially for reducing the ends of turbine blades to a fine edge.

15 The invention consists in a blade shaping machine comprising a blade carrier, means for clamping blade metal thereon, a cutting tool and means for producing relative movement between the blade and cutting tool whereby metal may be cut away from the blade end so as to thin its end to a substantially uniform cross sectional thickness from one edge to the other edge of the turbine blade.

25 According to the invention, the machine has a rotatable blade carrier to which is pivotally attached a member which is adapted to hold a blade upon the carrier and then to move the blade against the rotating cutter whereby the blade end is reduced, then to release the blade and to restore the carrier to its initial position ready for the insertion of another blade.

With most small turbine blades the 35 concave surface of the blade approximates sufficiently to an arc of a circle to insure a practically even cross-section of blade after the reduction has taken place without movement between the axes of the blade mandrel 40 and cutter spindle, but for large and flatter blades this is not accurate enough. Accuracy with large blades is obtained however by arranging for relative movement to take place between the axes of the cutter 45 and blade mandrel regulated in amount by an adjustable former.

Referring now to the accompanying drawings:—Figures 1, 2 and 3 are side, end and plan views respectively of a blade end reducing machine according to one form of the invention. Fig. 4 is a cross sectional view of the machine on line A B of Fig. 1. Figs. 5, 6 and 7 are side, end and plan views respectively of a modified form of blade 55 end reducing machine, the blade not being

shown in position on the mandrel in these views. Fig. 8 is a cross sectional view on the line C. D. of Fig. 5, and showing the blade in position on the mandrel. Figs. 9 and 10 are fragmental views of the end of 60 a mandrel of the form shown in Figs. 5 to 8 of the drawings. Figs. 11 and 12 are detail views partly in section of the slotted jaw mechanism, Fig. 12 being a view at right angles to Fig. 11.

In carrying the invention into effect as shown in Figs. 1 to 4 which illustrate a form especially suitable for blades of somewhat small size or blades which are formed with their concave sides curved approximately to an arc of a circle, we provide a milling cutter, *a*, on a spindle *b*, supported in bearings, *c* and *d*, on a bed plate *e*. Approximately parallel to the cutter shaft is a blade carrying mandrel, *m*, mounted in 75 bearings so that it may be adjustable in relation to the cutter shaft, as for instance, by supporting one end of it in a pivotally mounted bearing, *j*, and the other in a 80 slide bearing, *g*, secured to the bed plate by a set screw, *h*, passing through a slotted hole, *i*, in the bearing block, a spring *k*, being interposed between the slide bearing block and a buttress, *l*, and a thumb screw, *o*, being passed through an extension, *n*, 85 to bear against the block. The bearing *j*, is held by a machined set screw, *p*. On the mandrel is a projecting strip of metal *q*, formed by a long key or feather for supporting or guiding the blade in its proper 90 position and so preventing the blade from falling when released by the hand of the operator. To the mandrel there is also secured a fulcrum block or lug, *r*, having a slotted jaw as shown which forms a pivotal 95 connection for a lever, *s*, having a toe piece, *t*, as shown clearly in Fig. 2 and also in regard to the other modification in Fig. 8 this toe piece being adapted to clamp the blade, 18, firmly upon the mandrel by the initial movement of the lever in an upward direction after which continued movement in the same direction rotates the mandrel. The end of the slotted jaw forms an abutment against which the lower edge of the lever, *s*, contacts when said lever is moved in a downward direction by which means the mandrel may be rotated back to its original position after having been moved as 100 previously described.

110

In the standard *g* is a small rod, *u*, having a projecting portion, *v*, which acts as a distance stop for the blade when the latter is placed on the mandrel with its end opposite the cutter, *a*, this rod being adjustably held by means of a screw, *w*, in the standard block *g*. The cutter spindle may be rotated by any convenient means, as for instance by a belt on a pulley, *x*. The mandrel or blade carrier, *m*, is provided with some suitable friction or other resistance to retard its motion, a convenient means being a pulley, *y*, over which passes a strap brake *z*, the frictional effect of which may be adjusted by means of the thumb nut 2. The rotary movement of the mandrel in both directions is limited by suitable stops, as for instance by securing on the mandrel a collar, 3, having two projecting faces adapted to engage with a stop 4 extending from the bearing block *j*.

The operation of the machine is as follows:—A blade is placed on the mandrel, *m*, against the strip, *q*, and is slid along until the end which is to be reduced bears against the distance stop, *v*. The lever, *s*, is then moved forward. The initial part of the movement of the lever causes the piece to grip the blade firmly on the mandrel, and the further movement causes rotation of the mandrel and blade carried by it. The blade is thus carried against the rotating cutter, *a*, which in consequence removes some of the metal from the convex side of the blade at its tip. After the blade has been moved beyond the reach of the milling tool, the handle is moved backward. The first part of this backward movement unclamps the reduced blade which drops into a receptacle, the remainder of the movement effecting the restoration of the carrier or mandrel to its initial position, when it is ready to deal with another blade, these operations being repeated as rapidly as desired. The concave surface of small blades being in most cases approximately an arc of a circle, it is found that when the blade is held on the mandrel and the latter suitably rotated in proximity to the milling cutter, the desired amount of metal may be removed from the back of the blade to leave the reduced cross section practically even. Where, however, it is desired to reduce the ends of blades of cross section the concavity of which differs considerably from an arc of a circle, it is desirable in order to obtain an even reduced edge, to arrange for some relative movement to take place between the axes of the cutter spindle and mandrel while the latter is being rotated. This movement may be effected by any convenient means as for instance as shown in Figs. 5 to 8 by providing on the mandrel, *m*, a former 15 firmly held to it by the collar, 30, and the screw, 16, which engages

with the eccentric, 12, adjustably clamped against the bearing, *c*, by the screw 13 and plate 14. The bearings, *c* and *d*, for the cutter spindle, *b*, are formed in one piece with the arm, 19, and the whole is pivoted to the bed-plate, *e*, by the pin, 20. The spring 11, tilts the cutter spindle bearings toward the blade mandrel the eccentric being normally brought into contact with the former thereby, while the adjustment of the eccentric, 12, determines the minimum distance between the cutter spindle and the mandrel. After a blade has been placed on the mandrel, the lever, *s*, is moved forward clamping the blade on the mandrel by its initial movement and rotating the mandrel by its further movement. As the mandrel rotates, the former, 15, comes into contact with the eccentric, 12, while the turbine blade is carried against the milling cutter. The shape of the former, 15, must of course be determined from the section of the blade to be operated upon as will be readily understood, and the amount of metal removed from the blade tip is adjusted by varying the position of the eccentric about the cutter spindle. The blade end may thus be milled so that the convex surface corresponds practically in contour or curvature with the concave face of the blade. By providing the cutter spindle with a circular saw, 85, of slightly larger diameter than the milling cutter, the blades previously operated upon may be cut off from a length of strip at the same time as the reduction of another blade end is taking place. The brake sleeve or pulley, *y*, fixed to the blade mandrel, is in this case, provided with a longitudinal groove, to allow the strip to be inserted from the end toward the cutter *a*. The mandrel is formed with a clearance recess 17 opposite the saw. The length of the cut blade is of course determined by the amount of blade strip which is fed forward at one time and the distance between the recess in the mandrel opposite the saw, 85, and the collar, 30, on the mandrel close to the bearing *c*, determine the longest length of blade that can be cut off by the machine. It will of course be understood that the distance stop, *v*, is only used when separate blade pieces are placed on the mandrel by hand to be operated on and is removed when the blade strip is fed automatically along the mandrel.

Having now described our invention what we claim as new and desire to secure by Letters Patent is:—

1. In combination in a machine for shaping turbine blades, a blade carrying mandrel, a lever having one long and one short arm pivoted on said mandrel, said lever operating to rotate said mandrel after a small rotational movement about its own pivot when said long arm is moved in either

direction and said short arm acting to clamp a blade to the mandrel when the long arm is moved in one direction and releasing said blade when said long arm is moved in the opposite direction.

2. In combination in a machine for shaping turbine blades, a blade carrying mandrel, a rotary cutter, a spindle carrying said cutter disposed parallel to said mandrel, a lever having one long and one short arm pivoted on said mandrel, said lever operating to rotate said mandrel after a small rotational movement about its own pivot when said long arm is moved in either direction and said short arm acting to clamp a blade to the mandrel when the long arm is moved in one direction and releasing said blade when said long arm is moved in the opposite direction.

3. In combination in a machine for shaping turbine blades, a blade carrying mandrel, a former mounted thereon, a rotary cutter, a spindle carrying said cutter disposed parallel to said mandrel, movable bearings for said spindle, an eccentric adjustably clamped against one of said bearings and adapted to bear against said former and acting to regulate the distance of the axis of the cutter spindle from the blade carrying mandrel, a spring acting to yieldingly draw the axis of the cutter spindle toward the blade carrying mandrel, a lever having one long and one short arm pivoted on said mandrel, said lever engaging to rotate said mandrel after a small rotational movement about its own pivot when said long arm is moved in either direction and said short arm acting to clamp a blade to the mandrel when the long arm is moved in one direction and releasing said blade when said long arm is moved in the opposite direction.

4. In combination in a machine for shaping turbine blades, a blade carrying mandrel, a slotted lug attached to said mandrel, a pivot parallel to said mandrel passing across said slot in said lug, a manually operated lever having a long and a short arm working on said pivot in said slot, a gripping part formed at the end of said short arm, which arm is so shaped that its end approaches said mandrel to clamp a blade thereto when said long arm is moved in an upward direction after which further movement of said long arm tends to rotate said mandrel and a surface forming the end of said slot against which said long arm acts when moved in the reverse direction to return said mandrel to its original position.

5. In combination in a machine for shaping turbine blades, a blade carrying mandrel, a rotary cutter, a spindle carrying said cutter disposed parallel to said mandrel, a slotted lug attached to said mandrel, a pivot parallel to said mandrel passing across said

slot in said lug, a manually operated lever having a long and a short arm working on said pivot in said slot, a gripping part formed at the end of said short arm, which arm is so shaped that its end approaches 70 said mandrel to clamp a blade thereto when said long arm is moved in an upward direction after which further movement of said long arm tends to present said blade to said cutter by rotating said mandrel and a surface forming the end of said slot against which said long arm acts when moved in the reverse direction to return said mandrel to its original position.

6. In combination in a machine for shaping turbine blades, a blade carrying mandrel, a former mounted thereon, a rotary cutter, a spindle carrying said cutter disposed parallel to said mandrel, movable bearings for said spindle, an eccentric adjustably clamped against one of said bearings and adapted to bear against said former and actuating to regulate the distance of the axis of the cutter spindle from the blade carrying mandrel, a spring acting to yieldingly draw the axis 90 of the cutter spindle toward the blade carrying mandrel, a slotted lug attached to said mandrel, a pivot parallel to said mandrel passing across said slot in said lug, a manually operated lever having a long and a short arm working on said pivot in said slot, a gripping part formed at the end of said short arm, which arm is so shaped that its end approaches said mandrel to clamp a 95 blade thereto when said long arm is moved in an upward direction after which further movement of said long arm tends to present said blade to said cutter by rotating said mandrel, and a surface forming the end of said slot against which said long arm acts when moved in the reverse direction to return said mandrel to its original position. 105

7. In combination in a machine for shaping turbine blades, a blade carrying mandrel, a slotted lug attached to said mandrel, a pivot parallel to said mandrel passing across said slot in said lug, a manually operated lever having a long and a short arm working on said pivot in said slot, a gripping part formed at the end of said short arm, which arm so shaped that its end approaches said mandrel to clamp a blade thereto when said long arm is moved in an upward direction, brake means on the blade carrying mandrel to hold same while said blade is so clamped, after which further movement of said long arm tends to rotate said mandrel, a surface forming the end of said slot against which said long arm acts when moved in the reverse direction to return said mandrel to the original position. 110 115 120 125

8. In combination in a machine for shaping turbine blades, a blade carrying mandrel, a rotary cutter, a spindle carrying said cutter disposed parallel to said mandrel, a 130

slotted lug attached to said mandrel, a pivot parallel to said mandrel passing across said slot in said lug, a manually operated lever having a long and a short arm working on 5 said pivot in said slot, a gripping part formed at the end of said short arm, which arm is so shaped that its end approaches said mandrel to clamp a blade thereto when said long arm is moved in an upward direction, 10 brake means on the blade carrying mandrel to hold same while said blade is so clamped, after which further movement of said long arm tends to present said blade to said cutter by rotating said mandrel, and a surface forming 15 the end of said slot against which said long arm acts when moved in the reverse direction to return said mandrel to its original position.

9. In combination in a machine for shaping turbine blades, a blade carrying mandrel, a former mounted thereon, a rotary cutter, a spindle carrying said cutter disposed parallel to said mandrel, movable 20 bearings for said spindle, an eccentric adjustably clamped against one of said bearings and adapted to bear against said former 25 and acting to regulate the distance of the axis of the cutter spindle from the blade

carrying mandrel, a spring acting to yieldingly draw the axis of the cutter spindle 30 toward the blade carrying mandrel, a slotted lug attached to said mandrel, a pivot parallel to said mandrel passing across said slot in said lug, a manually operated lever having 35 a long and a short arm working on said pivot in said slot, a gripping part formed at the end of said short arm, which arm is so shaped that its end approaches said mandrel to clamp a blade thereto when said long 40 arm is moved in an upward direction, brake means on the blade carrying mandrel to hold same while said blade is so clamped, after which further movement of said long arm tends to present said blade to said cutter by rotating said mandrel and a surface 45 forming the end of said slot against which said long arm acts when moved in the reverse direction to return said mandrel to its original position.

In testimony whereof, we affix our signatures in presence of two witnesses.
